Dec. 1125

David Hathaway of Troy, N.Y.
Assignor to Fuller, Warren & Co. of same place.
Letters Patent No 1125. Dated July 26. 1859.

The schedule referred to in these Letters Patent and making part of the same.

To all whom it may concern:

It is known that I, David Hathaway, of the City of Troy,
in the County of Rensselaer, and State of New York, have invented or produced a new
and original Ornamental Design for a Cook Stove, and I do hereby declare that the
following is a full and exact description of the same, reference being had to the annexed
Photographic drawings making a part of this Specification, in which the photograph
on sheet

1. represents the front, and that on sheet
2. a side, of a Cook Stove.

My ornamental design for the front and sides of a Cook Stove, consists
of an altar-piece, a, on each large door of the front, and a compound ornament composed
of scroll-leaves, d, and flower and fruit branches, b, within a border-molding, c, a cen-
sor, e, surrounded by a molding, f, and a niche-piece, g, on each side: the whole being so
formed and arranged as to produce the same appearance as is represented in the an-
nexed photographic drawings.

What I claim as my invention or production and desire to secure
by Letters Patent is the ornamental design, for the front and sides of a Cook Stove, here-
in described.
